SMOKER'S ACCESSORY

Joseph N. Amigone, Buffalo, N. Y.

Application May 24, 1955, Serial No. 36,187

Term of patent 14 years

(Cl. D85—7)

Fig. 1.

Fig. 2.

Fig. 3.

Fig. 4.

Fig. 1 is a top plan view of a smoker's accessory showing my new design;

Fig. 2 is a side elevational view showing one side thereof;

Fig. 3 is a side elevational view showing the other side thereof; and

Fig. 4 is a bottom plan view thereof.

I claim:

The ornamental design for a smoker's accessory, as shown.
